OPEN-BACK-TYPE SHOE CONSTRUCTION

Abraham M. Rogoff, Boston, Mass., assignor of
one-half to Saul E. Erlich, Malden, Mass.

Application July 30, 1945, Serial No. 607,719

5 Claims. (Cl. 36—19.5)

1

This invention relates to improvements in shoes and their method of manufacture, and especially to ladies' shoes of the type commonly referred to as "open-back" shoes.

An object of the invention is to improve shoes and methods of making shoes in general, and to devise a cheap, efficient and rapid method of manufacturing ladies' shoes of the open-back type while providing for better fit, improved appearance and simplicity of construction. Other objects will appear from the following description.

In the accompanying drawings:

Fig. 1 is a plan view of a shoe upper member;

Fig. 2 is a plan view of the shoe lining member 15 of the invention;

Fig. 3 is another plan view illustrating attachment of the lining member to the upper member;

Fig. 4 is a plan view of an inner sole member;

Fig. 5 is a plan view illustrating attachment of 20 the inner sole member to the lining member;

Fig. 6 is a cross section taken on the line 6—6 of Fig. 5;

Fig. 7 is another plan view illustrating another step in the method of the invention;

Fig. 8 is a cross section taken on the line 8—8 of Fig. 7; and

Fig. 9 is a perspective view of the finished shoe of the invention.

In constructing my improved shoe, I provide a shoe top or upper member 10 which may be composed of any suitable material generally used for this purpose, and preferably consisting of a fabric material. The upper member is cut out in conventional manner in a shape common to ladies' shoes of the open-back type, as shown in Fig. 1. Numeral 12 denotes a V-shaped opening at the toe portion of the upper; 14 denotes an elongated slot forming the tongue area; and 16 indicates a heel strap portion.

I next provide a lining member 18 (Fig. 2), which may be of fabric or other material, and which is similarly formed with a V-shaped opening 20, an elongated slot 22 and a heel strap 24. The general shape of the lining is similar to that of the upper member 10; however, the lining is purposely made smaller all along its outer border so that when the lining is placed on the upper, the latter extends beyond the edges of the lining to provide a marginal edge 26, as may be better seen in Fig. 3. In addition the lining member is further cut away at the toe portion and at the quarter portions to leave openings or notches 28 and 30 respectively, which provide clearances for subsequent stitching operations.

The lining member is preferably provided with an unfinished side having a soft flannel-like surface. This unfinished side is covered with an adhesive 32 such as rubber cement or other substance over its entire surface excepting an outer

60 marginal border approximately one-half to three-quarters of an inch wide which is left uncovered by the cement. The treated side of the lining is then cemented to the upper member in the manner indicated in Fig. 3.

The free edges of the toe portions of upper 10 and lining 18 are then secured together and finished by stitching a cord member 34 along these portions, as has also been indicated in Fig. 3. Similarly, free edges of the upper and lining along the back portions are secured together and finished by means of a second cord member 36.

It is pointed out that the notches 28 and 30 in the lining member are of some convenient width such as for example one-eighth of an inch, which permits the cord members 34 and 36 to be stitched in place without completely securing the front and rear edges of the lining to the upper and permitting a marginal edge portion of the liner to remain unattached so that it can be freely folded away from the upper member.

The upper and lining assembly is temporarily laid aside and an inner sole member 40 (Fig. 4) is provided, to which is cemented a covering or sock lining 42 which is formed with overlapping heel and toe portions folded over the edges of the inner sole and secured as shown in Fig. 4.

I next arrange the upper member 10 above the finished side of the insole member 40, and then stitch the uncemented marginal edge portions of the lining member, left free by the notches 28 and 30, to the insole, leaving the overlapping marginal edges of the upper member extending out over the inner sole border. While the upper member remains in this position with its outer edges unengaged, a slip-lasting operation is carried out by inserting a last member between the lining and inner sole, and forming the upper and lining assembly to a desired shape.

While the last is in place, with the upper and lining member properly adjusted with respect to one another, the outer marginal edge of the upper member is pulled over the edge of the inner sole; folded against its under side; and cemented in the manner illustrated in Fig. 7. I may also desire at this point to attach to the upper portion a fastening of some convenient type such as the buckle 44 illustrated in Figs. 5 and 6. The strap portion of the upper is designed to engage with the buckle. If desired, a suitable stiffening member such as the shank element 46 is inserted against the under side of the inner sole member and thereafter an outer sole 48 is applied over the inner sole in some suitable manner as for example by a conventional cementing process.

The method and construction described may be subject to various modifications, both in arrangement and in materials employed. Other types of shoes than the particular class referred to may

be made in this manner, and various other modifications resorted to.

An important feature of the method is the step of carrying out the lasting operation while the upper member is secured to the lining member only. This is possible by the novel step of securing the lining member to the upper member by means of adhesive materials and at the same time leaving an unattached marginal lining edge which can be stitched to the inner sole in the manner described. By carrying out a lasting operation at the point referred to, it is possible to save a great deal of time, do less work, and consequently to achieve material savings in the manufacture of a shoe. At the same time, the lasting operation carried out under these conditions tends to provide better shape and appearance with a minimum of effort since the cemented relation of the two members tends to permit a certain amount of yieldability which permits the two members to adjust themselves relative to one another in producing a properly lasted shape. This lasted effect is one which takes place over the whole shoe upper without being dependent upon shaping effects obtained by stitching or fastening the upper member progressively along the edges to a sole member in the conventional manner.

It is also a desirable attribute of the method of the invention that the sock lining member is already installed during the process, thus tending to eliminate a separate application of this member after the main body of the shoe has been finished. Another striking advantage of the shoe is its exceptional flexibility as to the different types of sole materials dealt with. It is not necessary in the method of the invention to utilize a so-called heavy sole or heavy platform. A very thin sole works equally as well as a heavy sole. Attention is also directed to the feature of cutting notches in the lasting member which provides a free marginal lining edge which may be stitched to an insole while leaving the upper member with an unattached overlapping marginal edge. Various other advantages are also found, both in connection with the shoe construction and the method of manufacture described.

While I have shown a preferred embodiment of the invention, it is understood that various other changes and additions may be resorted to in connection with the invention as defined by the appended claims.

I claim:

1. That improved method of making shoes which comprises providing a lining member with marginal side edges which are defined by front and rear notches, attaching the lining member to an upper member throughout a part only of the width of the lining member to leave the marginal edges of the lining member separated from the upper, then applying a cord member at front and rear portions of adjacent edges of the lining member and upper member, said cord member being so applied as to be separated from the lower edges of the lining by said notches, then stitching the marginal side edges of the lining, lying between those edges secured by the cord members, to an inner sole member which has been covered with a sock lining, then lasting the shoe, then securing the marginal portions of the upper member to an inner sole, and then applying an outer sole member.

2. An improved shoe of the open-back type comprising an outer sole, an inner sole secured

to the outer sole, an upper member cut away to provide an open heel portion and an open toe portion, marginal edges of the upper being folded around the under side of the inner sole and secured between this member and the outer sole, a sock lining secured upon the inner sole, a tab portion integral with the sock lining folded around the edge of the inner sole at points occurring along the open toe portions of the shoe, a lining member secured to the upper, said lining being stitched to the said sock lining and the inner sole.

5 3. An improved shoe of the open-back type comprising an outer sole, an inner sole secured to the outer sole, an upper member cut away to provide an open heel portion and an open toe portion, marginal edges of the upper being folded around the under side of the inner sole and secured between this member and the outer sole; a sock lining secured upon the inner sole; a tab portion integral with the sock lining folded around the edge of the inner sole at points occurring along the open heel portion of the shoe; a lining member secured to the upper, said lining having a marginal edge folded over and stitched to the said sock lining and the inner sole.

20 4. An improved shoe of the open-back type comprising an outer sole; an inner sole secured to the outer sole; an upper member cut away to provide an open heel portion and an open toe portion; marginal edges of the upper being folded around the under side of the inner sole and secured between this member and the outer sole; a sock lining secured upon the inner sole, means for covering the edges of the inner sole at points occurring along the open toe portion of the shoe; a lining member cemented to the upper, said lining having front and rear edge portions secured to adjacent edges of the said upper by lines of stitching; said lining further being formed with notched marginal side edges terminating within the said lines of stitching; and said notched marginal side edges being secured to the sock lining and inner sole.

25 5. In a method of making shoes of the open-back type, the steps which include providing an upper member and a lining member, said lining member having interrupted marginal edges; securing front and rear portions of the interrupted marginal edges to adjacent edges of the upper by lines of stitching which leave intervening side edges of the lining free to be folded back upon themselves; stitching the free side edges to an insole member while the side edges are in a partly folded position with extremities of the said front and rear stitched edges lying against the insole member; said insole member including a sock lining with folded tab portions secured at the under side of the inner sole; slip lasting; securing upper marginal portions at the bottom of the insole, and applying an outer sole member.
